UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,392, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The accompanying drawing represents sufficient of a shawl-pattern to illustrate my design, the principal features of which are the alternate wide and narrow stripes A and B and intervening plain body C, the said stripes being variegated in shade or color, and each composed of a number of minor parallel stripes, bars, or ribs, of varying widths, some being strongly contrasted, and others blended or shaded into each other, as shown. The wide stripe A has at each side of its center a two

parallel ribs, b b, the central portion of each of which is occupied by a series of rectangular or oblong dots, presenting the appearance of a broken longitudinal stripe. The central rib d of the stripe B is similar to the ribs b.

Irrespective of the colors employed, I claim—

1. The design for the stripe A, as represented.
2. The design for the whole pattern, including the stripes A and B.

In testimony whereof I have signed my name to this specification in the presence of two subscribing witnesses.

FRED. WINK.

Witnesses:

WM. A. STEEL,
HUBERT HOWSON.
